UNITED STATES PATENT OFFICE.

JOHN D. BANKS, OF COLWYN, PENNSYLVANIA, ASSIGNOR, BY MESNE AND DIRECT AS-
SIGNMENTS, TO KIL-GLAR COMPANY, OF AUDUBON, NEW JERSEY.

GLARE SHIELD FOR AUTOMOBILES.

Application filed June 19, 1920. Serial No. 390,091.

To all whom it may concern:

Be it known that I, JOHN D. BANKS, a citizen of the United States, residing at Colwyn, in the county of Delaware and 5 State of Pennsylvania, have invented certain new and useful Improvements in Glare Shields for Automobiles, of which the following is a specification.

It is well known that drivers of automobiles are often temporarily blinded by the glare of head lights of other on-coming cars and that accidents often occur due to the fact that a driver thus temporarily blinded can not see the roadway and steers either 10 into the on-coming car or into a ditch or obstacle at the side of the roadway. Even though no accident results it is decidedly unpleasant to have the strong light glare projected directly in the face every time a 15 car passes which is going in the opposite direction. Numerous devices have been invented to shield drivers from the glare of head lights of on-coming cars and while they serve to some extent to shield the 20 driver from glare at close range, they fail in two particulars or conditions. In the first place they do not absorb the glare when the on-coming car is at a comparatively great distance and continue to shield the 25 driver until the car has passed him and at the same time permit said driver to clearly see the roadway immediately in front of him. In the second place they do not shield the driver from the glare of a car on a 30 bend or curve ahead and to the right and at the same time permit him to clearly see the roadway immediately in front of him.

One object of my present invention is to provide an improved glare shield of a 35 practical, simple and durable construction which will serve to absorb the glare of head lights under all of the above mentioned conditions.

A further object is to provide, in one 40 form of my invention, a structure which can be attached to a wind-shield of any of the well known types and if desired can be moved into a position out of the line of driving vision of the driver.

50 These objects, and other advantageous ends which will be described hereinafter, I attain in the following manner, reference being had to the accompanying drawings in which—

55 Figure 1 is a front elevation showing one

form of my invention as it appears when in operative position attached to the frame of a wind-shield of a well known type,

Figure 2 is a section taken on the line 2—2 of Figure 1 and showing in dot-and-dash line position the direction in which the glare shield proper can be swung into and out of operative position,

Figure 3 is a view looking at the opposite side of Figure 1; the glass of the wind-shield being omitted and the part of the supporting frame of the wind-shield being illustrated in dot-and-dash lines,

Figure 4 is a fragmentary section taken on the line 4—4 of Figure 3,

Figure 5 is a section taken on the line 5—5 of Figure 3,

Figure 6 is a section taken on the line 6—6 of Figure 3,

Figure 7 is a detail view of the shield frame,

Figure 8 is an elevation showing a modified form of my invention wherein the shield member is inserted directly in the plane of the usual clear glass of a wind-shield,

Figure 9 is a section taken on the line 9—9 of Figure 8,

Figure 10 shows another form of my invention where the glare shield is applied to the surface of the usual clear glass wind shield and,

Figure 11 is a section taken on the line 11—11 of Figure 10.

Referring to the drawings and particularly to the form of my invention shown in Figures 1 to 7 inclusive, 15 represents a wind-shield which may be of any of the usual types including a clear glass 16 and a frame 17; only a portion of the glass and an upright left hand post 18 of the wind-shield being illustrated. My invention includes a bracket 19 having an arm 20. The arm 20 has an upright groove 21 at its lowermost portion which is opposite a corresponding groove 22 in a clamping plate 100 23; said clamping plate being adapted to be secured by clamping bolts 24. The upright post 18 of the wind-shield, when the device is in operative position as shown in Figures 1 and 2, extends upwardly through the grooves 21 and 22 and the clamping bolts 24 serve to adjustably secure the bracket to the post 18; the clamping bolts extending through holes in the arm and plate at the outer side of the post 18 as 105 110

clearly shown in Figure 1. The arm 20 extends upwardly at a slight slant as shown in Figure 2 and at its top includes a bore 25 for pivotally retaining the trunnion or pin 26 of a shield frame 27. The portion of the bracket above the bore 25 is split and includes projecting ears 28 and 29 through which pass a clamping screw 30 so that by tightening on the clamping screw the shield frame can be held in any desired pivotal position but is permitted to be swung inwardly as shown in the dot-and-dash line position in Figure 2. The trunnion or pin 26 projects in a substantially horizontal direction from the upper left hand corner of the shield frame 27; said shield frame including a substantially horizontal top leg 31 and a depending leg 32. The leg 32 is arranged at the left hand side of the shield frame and includes a forwardly projecting rib 33 which meets at its top a forwardly projecting rib 34 which extends lengthwise of the top leg 31 as clearly shown in Figures 3 and 7. These ribs 33 and 34 are positioned within the width of the respective legs and form a ledge for abutment with the top and left hand edge portions of a glare shield member 35. The glare shield member 35 is preferably made of a piece of amber colored plate glass of the shape clearly shown in Figures 1 and 3 and is secured to the shield frame 27 by means of clips 36, 37 and 38. These clips embrace the forward surface of the shield member 35; the clip 38 having a shoulder 39 for supporting the lower left hand corner of the shield member 35 while the clip 37 has a shoulder 40 for holding the upper right hand edge of the shield member 35. The upper left hand corner of the shield member 35 is held in place by the clip 36 and each of the clips 36, 37 and 38 have removable screws 41 which fit in tapped holes in the shield frame. In this manner the glass shield member 35 is secured to the shield frame 27 and I preferably employ rubber shrouding members 42 for embracing the glass parts which are engaged by the clips. The shape of the exposed portion of the glass shield member 35 forms a very important part of my present invention as previously inferred in the objects of the invention and I will therefore describe the shape of my improved shield member specifically.

The shield member 35 includes a main portion α which extends from top to bottom at the left hand side thereof. From this portion α , a part α^1 projects continuously toward the right at the upper portion of the member so that the bottom edge 43 of the part α^1 is above the level of the lower edge 44 of the part α .

In the form of my invention shown in Figures 1 to 7 inclusive, the bottom edge 43

of the part α^1 at a point y inwardly from the outer right hand edge 45 curves downwardly to the left as shown at 46 and at its bottom joins the edge 44 of the part α . Thus the part α^1 gradually increases in width toward 70 the left and the edge 43 from the point y becomes gradually lower until it meets the edge 44. In other words, the part α^1 forms an arm which extends from the part α ; the arm becoming narrower as it approaches the 75 point y and also arranged at a higher level than the bottom of the part α . By thus constructing the member 35, an indentation or clear sight passage 47 is produced; said clear sight passage being positioned to the right 80 of the lower portion of the part α of the shield member 35 and extending above the level of the edge 44 and below the edge 43 of the part α^1 . By positioning the device so that the clear sight passage 47 is practically 85 in front of the eyes of the driver of an automobile upon which the device is placed, the parts α and α^1 provide a glare absorbing zone which is of a scope capable of taking in the light rays of the head lights of on-coming 90 vehicles irrespective of their distance away or the curvature of the roadway ahead of the driver. For example a driver looking through the glare shield member 35 will see at a distance, through the upper portion 95 thereof, an on-coming vehicle and as the vehicle approaches it will gradually be seen through lower and lower portions of the parts α . If the on-coming vehicle is initially 100 observed at a distance on a right hand turn 105 of the road, the vehicle will be seen through the portion α^1 and as it approaches, it will be seen in gradually lowering portions of the member 35 until it can be seen through the portion α where said vehicle can be seen in 110 gradually lowering positions in said part α until the vehicle has passed.

Not only does the particularly formed glare shield member 35 present the above qualifications but it produces the clear sight 110 passage 47 through which the driver can observe the road a sufficient distance ahead of him to enable him to run the car without any possible chance of accident and his driving vision is not impaired.

In the form of my invention shown in Figures 8 and 9 instead of mounting the glare absorbing member 35 in a separate and adjustable frame as above described, I have shown the same in the plane of the clear 120 glass of the wind-shield and the glare absorbing member may be made of a separate piece of amber or other colored glass which is set in or it may be made integral with the clear glass and locked in any suitable manner.

In the form of my invention shown in Figures 10 and 11 the glare absorbing member 35 is pasted or otherwise secured directly 125 adjacent one surface of the glass of the

wind-shield and this may be done in any suitable manner such for example as by painting or cementing the glare absorbing member directly upon the glass of the wind-shield.

5 In each instance the glare shield or absorbing member is made of material which will absorb the glare of strong lights and is preferably made of translucent material 10 such as amber or yellow colored glass, celluloid or other suitable plate or sheet material.

While I have described my invention as taking a particular form, it will be understood that the various parts of my invention 15 may be changed without departing from the spirit thereof, and hence I do not limit myself to the precise construction set forth, but consider that I am at liberty to make such changes and alterations as fairly come within 20 in the scope of the appended claims.

Having thus described my invention, what I claim as new and desire to secure by Letters Patent is:—

1. A device of the character described including a translucent glare shield having a body portion and a comparatively narrow extension projecting laterally therefrom and terminating in a lower free edge portion which curves downwardly and merges into 30 the adjacent side edge of said body portion; substantially as described.

2. A glare shield having its shielding mar-

gin angularly positioned with respect to the vertical and horizontal.

3. A glare shield comprising a four-sided sheet of transparent material, said sheet having one edge inclined, with the upper edge longer than the lower edge.

4. In a vehicle having a wind shield provided with a pane, a transparent light screen 40 lying against and extending across the upper portion of the pane and having a transparent screen part extending downwardly at the side thereof, said screen being sufficiently transparent so that objects are visible in 45 sharp outline therethrough, but light-obstructing so that such objects appear under a reduced intensity of illumination, and the width of the transverse portion and the degree of downward extension of the screen 50 being proportioned to provide a maximum of uncovered glass with the continuous protection from the glare of the approaching headlight as the latter approaches and then moves to the side of the protected operator 55 in passing.

In testimony whereof I have signed my name to this specification in the presence of two subscribing witnesses.

JOHN D. BANKS.
